Inventor

Justus Verschuur,

By Drake & Co. Atty's.

UNITED STATES PATENT OFFICE.

JUSTUS VERSCHUUR, OF JERSEY CITY, NEW JERSEY.

DESIGN FOR A SPOON.

SPECIFICATION forming part of Design No. 21,550, dated May 17, 1892.

Application filed April 14, 1892. Serial No. 429,221. Term of patent 3½ years.

To all whom it may concern:

Be it known that I, JUSTUS VERSCHUUR, a citizen of the United States, residing at Jersey City, in the county of Hudson and State of New Jersey, have invented and produced a new and original Design for Spoons; and I do hereby declare the following to be a full, clear, and exact description of the invention, such as will enable others skilled in the art to which it appertains to make and use the same, reference being had to the accompanying drawing, and to letters of reference marked thereon, which form a part of this specification.

The single figure of the drawing is deemed sufficient but necessary to fully illustrate the design, and is a plan of the spoon having the desired decoration.

The leading feature of the invention is in the spoon having thistle-shaped ornamentation on the concaved face of the bowl, the said

ornamentation resembling the branch of the plant with stem, leaves, and flowers, substantially as shown.

In said drawing, A indicates the bowl of the spoon, and B the handle thereof. The surface of said spoon is ornamented with a thistle-shaped figure, of which *a* indicates the stalk, *b* the leaves, and *c c* the flowers, all resembling more or less closely the corresponding parts of the natural plant. 30

What I claim as new is—

The design for a spoon, herein shown and described.

In testimony that I claim the foregoing I have hereunto set my hand this 11th day of April, 1892. 35

JUSTUS VERSCHUUR.
